UNITED STATES PATENT OFFICE.

THOMAS RILEY, OF OELWEIN, IOWA.

PROTECTOR FOR SEWERS OF ENGINE CINDER-PITS.

1,349,734.

Specification of Letters Patent. Patented Aug. 17, 1920.

Application filed November 5, 1919. Serial No. 335,919.

To all whom it may concern:

Be it known that I, THOMAS RILEY, a citizen of the United States, resident of Oelwein, in the county of Fayette and State of Iowa, have made a certain new and useful Invention in Protectors for Sewers of Engine Cinder-Pits; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 The figure is a perspective view partly broken away of the invention, as applied.

The invention has relation to means for preventing cinders, mud and ashes from accumulating over and choking the mouths of 20 sewers of engine cinder pits of round houses, and it consists in the novel construction and combinations of parts as hereinafter set forth.

In the accompanying drawings illustrating the invention, the numeral 2 designates 25 the engine cinder pit, having side and end walls 3, and 4 is a horizontal grating, covering the sewer mouth, and located at one end of said pit, the latter having an inclined bottom 5, leading to the sewer.

In practice, cinders, mud and ashes accumulate in the pit and finding their way to the grating over the sewer mouth, collect thereupon and choke the grating, so that it 35 becomes rather frequently necessary to remove this accumulation in order that the sewer shall act.

The object of the invention is therefore to provide in addition to the aforesaid horizontal grating covering the sewer mouth, a

further guard or grating whereon cinders, mud and ashes may bank up at a point removed from the horizontal grating, thereby ordinarily preventing collection of cinders, etc. upon the horizontal grating; and in case 45 mud, ashes or fine stuff should sift through the additional grating over the horizontal grating and fail to pass through the latter to the sewer, opportunity is afforded for a workman to take a position over the horizontal grating and shovel away this accumulation to clear the way to the sewer. 50

This additional guard consists of an inclined grating 6 spanning the pit between the side walls thereof and located at one side of 55 the horizontal grating 4, being spaced apart therefrom at 7, the inclined grating being of finer mesh, about one half that of the horizontal grating 4, and being supported upon a skeleton frame 8, the sides or ends 8' of 60 which are in abutting relation to the side walls of the pit.

I claim:—

The combination with an engine cinder pit, having side and end walls, and a sewer opening at one end thereof, of a horizontal grating located over the mouth of the sewer and on a level with the floor of the pit, and an inclined grating of finer mesh than said horizontal grating and located transversely 70 of the pit at one side of said horizontal grating, the latter having a space thereover adapted for a workman to take place unobstructed by said inclined grating.

In testimony whereof I affix my signature 75 in presence of two witnesses.

THOMAS RILEY.
